SILENCER

Willis L. Manning, Madison, Wis., assignor to
 Burgess Battery Company, Chicago, Ill., a corporation of Wisconsin

Application July 1, 1938, Serial No. 216,856

15 Claims. (Cl. 181—54)

The present invention relates to silencers, and particularly to silencers for quieting the exhausts and intakes of internal combustion engines.

It is the object of the invention to provide a 5 silencer of simple design and economical construction which has high silencing efficiency throughout the frequency range usually encountered in internal combustion engines, and which interposes but slight restriction upon the flow there- 10 through.

Briefly, the invention provides a silencer of the retroverted passage type having conduits for the first and last passages but not for the intermediate passage, the sounds and gases employing the 15 space within the silencer casing for their passage between the first and last passages. The silencer also provides means whereby the gases at some point in their passage therethrough are caused to impinge upon a surface interposed directly across 20 their path to break up the high pressure slugs, the gases, however, being free to flow laterally of such means with substantially no restriction, with the result that but little restriction is caused by said means.

25 A silencer of such construction is particularly well adapted for silencing engine exhausts where a short tail pipe, or no tail pipe, is employed. In exhaust silencers which do not employ baffles a pipe of appreciable length is required to be connected between the outlet of the silencer and the atmosphere, this pipe being called a tail pipe and serving to load the silencer. This loading has been found to be necessary in order that the silencer function with effectiveness. In some 30 applications, because of space requirements, the use of a tail pipe of the requisite length is impracticable. The silencer of this invention is entirely effective without a tail pipe and hence is especially useful in the situations described. However, its 35 application is not limited to such situations, and it may be used in all the usual applications for silencers.

In the drawings:

Fig. 1 is a longitudinal view of one form of the 45 silencer of this invention;

Fig. 2 is a transverse sectional view along line 2—2 of Figs. 1 and 3;

Fig. 3 is a broken longitudinal sectional view along line 3—3 of Fig. 2;

50 Fig. 4 is a longitudinal view of a different form of the invention;

Fig. 5 is a transverse sectional view along line 5—5 of Figs. 4 and 6;

Fig. 6 is a broken longitudinal sectional view 55 along line 6—6 of Fig. 5;

Fig. 7 is a longitudinal sectional view of a further modification of the invention;

Fig. 8 is a longitudinal view of a further modification of the invention;

Fig. 9 is a broken longitudinal sectional view of 5 the modification shown in Fig. 8;

Fig. 10 is a transverse sectional view along line 10—10 of Fig. 9;

Figs. 11 and 13 are longitudinal sectional views 10 of further modifications of the invention; and

Figs. 12 and 14 are transverse sectional views along line 12—12 of Fig. 11 and line 14—14 of Fig. 13 respectively.

The silencer of Figs. 1, 2 and 3 comprises an 15 imperforate outer shell or casing 10, closed at its 19 ends by end walls 11 and 12. Said end walls have substantially central openings 13 and 14 therein, and inlet tube 15 and outlet tube 16 are mounted on said openings respectively. A number of 20 spaced transverse bulkheads or partitions 17, 18, 20 19 and 20 are provided within the interior of casing 10 to form a number of compartments or 25 chambers 21, 22, 23, 24 and 25. Partition 17 has eccentric openings 26 and 27 therein, said openings having relatively short, open-ended, perforated or foraminous tubes 28 and 29 mounted at one end in said openings and extending inwardly 30 toward partition 18, the inward open ends of tubes 28 and 29 being spaced from partition 18. The portion of partition 17 which is opposite the inlet 35 opening 13 is imperforate.

Partitions 18, 19 and 20 have central openings 40 therein and an open-ended tube 30, perforated throughout its length, is mounted at one end upon end wall 12 and extends through chambers 23, 24 45 and 25 and the said openings in partitions 18, 19 and 20 and partially through chamber 22 toward partition 17, the open end of tube 30 being spaced from said partition 17. Tube 30 is in alignment 50 with and connected to the outlet opening 14. 40 Tubes 28 and 29, extending from partition 17 into chamber 22, and tube 30 extending from partition 18 into the same chamber are coextensive within compartment 22 for a considerable proportion of the length of the said chamber. The tubes may 45 be in contact with one another as shown and may be fastened together, as by welding, to provide increased strength and rigidity. The chamber 25 surrounding tube 30 is filled with a suitable sound-absorbing and gas-pressure-absorbing material, 55 such as steel wool or other metallic wool, exfoliated vermiculite, asbestos fibers, rock wool, pumice and other loose ceramic aggregates, or aggregates bonded together with a suitable adhesive so as to provide intercommunicating pores and channels 55

within the material. The perforations or openings in the tubes 26 and 30 of this form of the invention, as well as the perforations or openings in the tubes of the modifications hereinafter to be described, may be other than round and may be larger or smaller than shown.

In operating the silencer as an exhaust silencer, tube 15 is connected to the exhaust pipe of the internal combustion engine and the exhaust gases enter the said tube, as indicated by the arrow in Fig. 3, and impinge against the imperforate central portion of partition 17. The slugs of gas under high pressure are broken by this impingement and the gas is free to expand and travel laterally within chamber 21, which it does and passes out of the said chamber through openings 26 and 27, and proceeds into perforated tubes 28 and 29. The gas passes from tubes 28 and 29 into chamber 22, and from said chamber into tube 30. A portion of the gas passes directly laterally from tubes 28 and 29 and into tube 30 through the perforations of the said tubes. Another portion passes through the said perforations in tubes 28 and 29 expands into the volume of chamber 22 with a resulting decrease of pressure. They then pass more slowly into tube 30 through the perforations and the open end thereof. A further portion travels as a stream out of the open ends of tubes 28 and 29, where it impinges against partition 18, reverses its direction and travels forwardly in the form of a converging stream to the forward end of chamber 22 where it impinges against partition 17 and again reverses its direction and passes into the open end of tube 30. The gases proceed through tube 30 and out of the silencer through the outlet opening 14 thereof, as indicated by the arrow in Fig. 3. In their impingements against the surfaces of partitions 17 and 18 the high pressure slugs of gas are broken and their intensity is reduced. The enclosed volumes of chambers 23 and 24 are connected to tube 30 by the perforations of the latter and constitute resonating chambers, which exert a silencing action upon the exhaust noises. The sound-absorbing material 31 in chamber 25 also exerts a silencing action.

The silencer described heretofore produces a highly effective silencing action, so that a relatively small silencer is required in comparison with silencers of different types. It is effective over the entire range of frequencies usually encountered in internal combustion engines, and possesses the property of substantially eliminating the slugs of high pressure gas which are only partially suppressed in many other types of silencer and which result in sharp cracks of noise, especially when the engine is performing under relatively heavy loads. The silencer does not require a tail pipe to give it effectiveness. The modification shown in Figs. 4, 5 and 6 comprises an imperforate casing 35 having end walls 36 and 37, end wall 36 having an inlet opening 38 therein, and end wall 37 having an outlet opening 39 therein, an inwardly extending flange 40 being provided at the opening 39. The silencer is adapted particularly for connection to flanged pipes, and for this purpose the end walls have stud bolts 41 threaded into them and adapted to have cooperating flanges fitted over them and fastened by suitable nuts against the surfaces of the said end walls.

The interior of casing 35 is provided with spaced, transverse partitions 42, 43 and 44 which divide the casing into chambers 45, 46, 47 and 48. Partition 42 is provided with eccentric openings

49 and 50, the central portion thereof, which is directly opposed to the entrance opening 38, being solid. Perforated tubes 51 and 52 are mounted at one end in openings 49 and 50 respectively and extend inwardly of chamber 46 a distance short of partition 43. Partitions 43 and 44 are provided with central openings and a perforated tube 53 is mounted at one end within flange 40 and extends forwardly through partitions 44 and 43 and into chamber 46 a distance short of the forward wall 42 thereof. Tubes 51 and 52 are coextensive with tube 53 for a portion of their lengths within chamber 46, and the tubes may be in contact with one another as shown and may be joined together as described heretofore in connection with the construction of Figs. 1, 2 and 3.

The operation of this silencer is similar to that of Figs. 1, 2 and 3. The construction is more rugged and adapted for more severe service. For example, sleeve members 54 are provided in the different partitions for the support of the tubes. The silencer of Figs. 1, 2 and 3 is in general, to be used where a smaller silencer is permissible and where the conditions of service are such that there is less vibration, shaking, etc.

The silencer of Fig. 7 comprises a casing 55 having end walls 56 and 57 and partitions 58 and 59, the latter dividing the interior of the casing into chambers 60, 61 and 62. The end walls have central openings 63 and 64 therein and an inlet tube connection 65 and an outlet tube connection 66 mounted in said openings respectively.

A relatively long perforated tube 67 is mounted at one end within the opening of end wall 56 and passes through a central opening in partition 58 and extends into chamber 61 stopping some distance short of partition 59. Partition 59 has two eccentric openings 68 and 69 mounted at one end within said openings and extend forwardly to within a short distance of partition 58.

In this construction the exhaust gases enter the silencer through entrance opening 63, as indicated by the arrow, and first encounter the silencing effect of resonating chamber 60. They proceed through perforated tube 67 into chamber 61 where some of them pass laterally through the openings of tube 67 and tubes 68 and 69 into the latter tubes, and others emerge longitudinally from the end of tube 67 and impinge upon the solid portion of partition 59, where the slugs of high pressure gas are broken as described heretofore, and the gas reverses its direction and flows forwardly in chamber 61 and passes through the perforations of tubes 68 and 69 into said tubes, some of it traversing the entire length of chamber 61 and reversing its direction at the forward end thereof and entering tubes 68 and 69 through the ends thereof. Slugs of high pressure gas passing forwardly in chamber 61 impinge against the surface of partition 58, and, likewise, any remaining slugs passing rearwardly within tubes 68 and 69 impinge against the solid surface of rearward end wall 57 and are again broken. At any of these impingements the gas slugs are free to expand and travel laterally so that a minimum of back pressure is created, but at the same time the slug-breaking action is effective, with the result that the gases emerge at opening 64 (as indicated by the arrow) in a stream which is sufficiently steady and uniform that no cracking noises or reports are created at the outlet of the silencer. In the construction of Fig. 7 the tubes within chamber 61 are spaced apart laterally, although they may be in

contact with one another as they are in the modifications described heretofore.

In the modification shown in Figs. 8, 9 and 10 the gas passes through two stages in each of which it undergoes two complete reversals of direction. This modification comprises an imperforate casing 70 having end walls 71 and 72, the end walls having openings 73 and 74 therein respectively and having inlet tube 75 and outlet tube 76 in said openings. An imperforate transverse partition 77 is located substantially centrally of the casing 70 and subdivides the casing into two chambers 78 and 79. Tubes 75 and 76 extend into chambers 78 and 79 toward transverse wall 77, the interior ends of said tube being spaced a substantial distance from said wall. The portion of the tubes 75 and 76 located within the said chambers are perforated, or foraminous. Four perforated, open ended tubes 80 are arranged longitudinally within casing 70 and about central tubes 75 and 76, tubes 80 passing through corresponding openings in transverse wall 77. The tubes 80 extend outwardly a substantial distance in both directions beyond the inner ends of tube 75 and 76. At or adjacent the left ends of tubes 80, as seen in Fig. 9, they are attached to the inlet tube 75, as by means of welding, and at or near the other ends they are fastened to outlet tube 76 by means of an annular plate or spider 81 having openings therein to accommodate the tubes. Outlet tube 76 is of slightly reduced diameter in comparison with tube 75 for the purpose of increasing somewhat the loading effect of this tube upon the silencer.

In this construction there are no resonating chambers such as are found in the constructions described heretofore. The gases enter chamber 78 through tube 75, as indicated by the arrow, where they pass from tube 75 to tubes 80 by an action similar to that described in connection with Fig. 7 during which they undergo a double reversal of direction. They then pass through tubes 80 into chamber 79 where they pass into outlet tube 76 in the manner described in connection with Figs. 1, 2 and 3, again undergoing a double reversal of direction. In this construction the absence of resonating chambers is compensated by the presence of the stage in which the gases undergo the second double reversal of direction. The fact that exit tube 76 is of slightly smaller diameter than inlet tube 75 results in an increased silencing effect.

The modification shown in Figs. 11 and 12 comprises an imperforate casing 90 having end walls 91 and 92, the end walls having central openings therein and tube connections 93 and 94 mounted in said openings. A transverse bulkhead or partition 95 is mounted within casing 90 adjacent and spaced from end wall 91. Bulkhead 95 has an eccentric opening therein and a perforated tube 96 is mounted at one end within said opening and extends toward the opposite end of the silencer. In a similar manner bulkhead 97 is mounted adjacent the other ends of the silencer and has an eccentric opening therein, in which is mounted a perforated tube 98 which extends toward bulkhead 95. The silencer is of symmetrical construction and either end may be used as the entrance. When tube 93 is the entrance tube the exhaust gases impinge against the solid portion of bulkhead 95 and expand and travel laterally and then pass into tube 96. The passage from tube 96 to tube 98 is in the manner described heretofore in connection with the earlier described modifications, some of the gases im-

pinging against bulkhead 97. After emerging from tube 98 some of them also impinge against end wall 92, after which they are free to expand laterally and pass out of the silencer through outlet tube 94.

In the modification illustrated in Figs. 13 and 14 one of the passages within the direction-reversing chamber is in the form of an annular conduit instead of a tube. The silencer comprises the imperforate casing 100 having end walls 101 and 102, end wall 101 having inlet connection 103, and end wall 102 having outlet connection 104 mounted therein. The perforated inlet tube 105 for the silencer is mounted in the opening of inlet end wall 101 and extends toward the opposite end of the casing. A perforated intermediate cylindrical shell 106 is spaced interiorly from casing 100 and extends from a point spaced from the rearward end of tube 105 forwardly to a point spaced from the forward end wall 101. The rearward end of intermediate shell 106 is closed by an imperforate plate 107. The intermediate shell is mounted adjacent its rearward end by means of brackets 108 which are supported by the casing 100, and is supported near its forward end by brackets 109 which extend between it and the inlet tube 105. The space between intermediate shell 106 and casing 100 forms an annular outlet conduit 110. The plate 107 forms a partition subdividing the casing into the direction-reversing chamber 111 and the chamber 112 at the rearward end of the casing, chamber 112 serving to connect outlet passage 110 to the outlet connection 104 of the silencer.

In this construction the gases enter tube 105 as indicated by the arrow, and some of them pass laterally through the openings of tube 105 and intermediate shell 106 into the outlet conduit 110, while others continue as a stream through the inlet tube and impinge against plate 107, where their direction is reversed and they travel forwardly through the interior of the direction-reversing chamber 111 and impinge against forward end wall 101, when their direction is again reversed and they pass rearwardly through outlet conduit 110 and into the chamber 112 at the outlet end of the silencer, and thence into the outlet connection 104. In this construction the direction of the gases may be reversed from that described.

In the silencers of this invention the area of the openings in the walls of the perforated tubes may be varied within limits of between approximately 0.01% and 10% of the area of the said walls. Within this range the opening area may be varied to secure the best performance for the particular application. In general, the attenuation becomes shifted to a lower frequency range as the proportion of open area becomes less. If the area of openings is outside the range stated the silencing is not effective throughout the frequency range required for satisfactory performance.

It is understood that the invention is not limited to the constructions specifically set forth but that variations may be made without departing from the scope of the invention. The outer casing need not be cylindrical as shown, but may be oval or angular in transverse shape. Sound-absorbing and gas-pressure-absorbing material may be placed in chambers other than chamber 25 of Fig. 3, or may be placed in additional chambers, and it may be placed in chamber 41 or 48 of the construction of Figs. 4, 5 and 6. The number, size and arrangement of the chambers

may be varied to suit the individual application of the silencer. The number, size, length and lateral arrangement of the tubes within the casting may be varied. Those portions of the tubes which pass through the resonating chambers of Figs. 1 to 7 inclusive may have one or more larger openings therein for making connection to the interior of the chambers, instead of being foraminous as described herein.

10 This application is a continuation in part of my co-pending application Serial No. 153,462, filed July 14, 1937.

I claim:

1. A silencer comprising a chamber having inlet and outlet openings in opposite walls thereof, open-ended inlet and outlet conduits arranged in juxtaposed relation within said chamber, said inlet and outlet conduits being connected at one end thereof to said inlet and outlet openings respectively and each extending from the wall opening to which it is connected part way toward the opposite wall and having an open end located within said chamber, said inlet and outlet conduits having openings in the walls thereof and being arranged laterally adjacent one another throughout a portion of their length, the open ends of said conduits located within said chamber being in free and unconfined communication with each other through the space within said chamber.

2. A silencer comprising a chamber having inlet and outlet openings in opposite walls thereof, perforated open-ended inlet and outlet conduits mounted in said inlet and outlet openings respectively, said inlet and outlet conduits being arranged in juxtaposed relation within said chamber and each extending from the wall opening in which it is mounted into said chamber part way toward the opposite wall, said inlet and outlet conduits being arranged laterally adjacent one another throughout a portion of their length, the open ends of said conduits located within said chamber being in free and unconfined communication with each other through the space within said chamber.

3. The silencer of claim 1 in which the chamber is substantially cylindrical and one of the inlet and outlet conduits is of annular shape and comprises the interior space contiguous to the cylindrical chamber wall, and the chamber opening connected to said annular conduit is also of annular shape.

4. The silencer of claim 1 in which the openings in the walls of said conduits occupy about 0.01% to 10% of the total area of the walls of said conduits.

5. A silencer comprising a substantially imperforate casing having inlet and outlet openings therein, at least one transverse partition within said casing providing a chamber within said casing, perforated open-ended inlet and outlet tubes mounted in opposite walls of said chamber and communicating with said inlet and outlet openings respectively, said tubes being offset laterally with respect to each other and each extending from the wall in which it is mounted into said chamber part way toward the opposite wall of said chamber and ending in adjacent spaced relation to said opposite wall, said oppositely extending tubes being arranged laterally adjacent one another throughout a portion of their length and being directly exposed to one another, the open end of said tubes located within said chamber being in free and unconfined communication

with each other through the space within said chamber.

6. The silencer of claim 5 in which at least one chamber wall has a plurality of openings therein and a perforated tube is mounted in each of said openings and extends toward but stops short of the opposite chamber wall.

7. The silencer of claim 5 in which at least one chamber wall has a plurality of openings therein and a perforated tube is mounted in each of said openings and extends toward but stops short of the opposite chamber wall and the adjacent portions of the perforated tubes extending from opposite chamber walls are united mechanically.

8. The silencer of claim 9 in which the first partition has a plurality of openings therein offset laterally with respect to the opening in the first end wall, and a perforated tube is mounted in each of said first partition openings and extends toward but stops short of the second partition.

9. A silencer comprising a substantially imperforate casing having inlet and outlet openings in opposite end walls thereof respectively, substantially imperforate transverse partitions within said casing and in spaced relation to each other, the first of said partitions being in adjacent spaced relation to the first of said end walls and having at least one opening therein offset laterally with respect to the opening in said first end wall, a perforated open-ended tube mounted in said first partition opening and extending part way toward the second of said partitions said second partition having an opening therein in alignment with the opening in said second casing end wall and offset laterally with respect to said perforated tube, a second perforated tube mounted in the opening in said second end wall and extending through said second partition and part way toward said first partition and ending in 40 adjacent, spaced relation to said first partition, said perforated tubes being arranged laterally adjacent each other for a portion of their lengths between said partitions.

10. The silencer of claim 9 in which the first end wall is the inlet end wall.

11. A silencer comprising an imperforate casing having inlet and outlet openings in opposite end walls thereof respectively and having a plurality of spaced apart, substantially imperforate transverse partitions subdividing the interior thereof into a plurality of chambers, the first of said partitions being spaced interiorly from the first of said end walls and having an opening therein offset laterally with respect to said opening in 55 said first end wall, a tube mounted in said first partition opening and extending toward but stopping short of the second of said partitions, said second partition and the remainder of said partitions having openings therein aligned with each other and with said opening in the second end wall, said aligned openings being offset with respect to said tube, a second tube connected to said outlet opening and extending through said aligned openings in said partitions and toward, 65 but stopping short of said first partition, said tubes being arranged laterally adjacent each other for a portion of their lengths between said first and second partitions and being perforated at their laterally adjacent portions, said second 70 tube having openings in the walls thereof communicating with those of said chambers through which it passes.

12. The silencer of claim 11 in which one or more of the chambers through which said second 75

- 5 tube passes contains porous sound-absorbing and
gas-pressure-absorbing material.
13. The silencer of claim 11 in which the openings
5 of the perforated portions of the tubes oc-
cupy about 0.01% to 10% of the area of the walls
of said portions.
14. A silencer comprising a substantially im-
perforate casing having inlet and outlet openings
in opposite end walls thereof respectively, sub-
stantially imperforate transverse bulkheads with-
in said casing and in adjacent spaced relation to
10 said end walls respectively, said bulkheads each
having an opening therein offset laterally with
respect to the opening in the adjacent end wall,
15 said openings in said bulkheads also being offset
laterally with respect to each other, and per-
forated tubes mounted in the openings in said
bulkheads respectively and extending part way
toward the opposite bulkheads and ending in
20 spaced relation to said bulkheads, said tubes being
arranged laterally adjacent each other for a por-
tion of their lengths.

15. A silencer comprising a substantially im-
perforate casing having inlet and outlet openings
in opposite end walls thereof respectively and
having a transverse partition therein dividing the
said casing into two chambers, open-ended inlet
and outlet tubes connected to said inlet and out-
let openings respectively and extending part way
toward said partition and ending in adjacent
spaced relation to said partition, said partition
having a plurality of openings therein, an open-
ended intermediate tube extending through each
10 of said openings and part way toward both end
walls of said casing and ending in spaced relation
to said end walls, said intermediate tubes being
displaced laterally with respect to said inlet and
outlet tubes and being arranged laterally adja-
cent said inlet and outlet tubes for a substantial
15 portion of their length, said inlet and outlet and
intermediate tubes having openings in the walls
thereof.

WILLIS L. MANNING.
